ORSON N. KELLY, OF LOS ANGELES, CALIFORNIA.

VENDING MACHINE.

Application filed February 14, 1925. Serial No. 9,129.

This invention relates to vending machines, and has for its object a machine adapted to contain commodities such as pie, cake, sandwiches, box lunches, chewing gum and the like, and responsive to a coin of proper denomination being placed in such machine, and in exchange for such coin to dispense a commodity.

The invention has for a further object the provision of a machine which is practically slug-proof and which will operate when a coin of proper denomination is received by such machine to discharge a commodity regardless of the fact that a slug has previously been inserted in the machine. This is an important object for the reason that the ordinary vending machines now on the market, as a rule, when a slug has been inserted in the coin-receiving chute and an attempted operation of the machine is made, upon the insertion of a proper coin the machine will refuse to operate, but as a rule will retain the coin.

Another object is the provision of a vending machine which is so constructed and formed that it is impossible to withdraw commodities from the machine by the insertion of wires or other objects through the commodity chute for the purpose of attempting to obtain such commodity or commodities without payment therefor.

Among other objects are simplicity of construction, inexpensiveness, practically a fool-proof machine, and one which will give continuous satisfactory service without much attention.

With the above and other objects in view, the invention consists in the novel and useful provision, formation, construction, association and relative arrangement of parts, members and features, all as detailed in a certain embodiment in the accompanying drawings, described generally and more particularly pointed out in claims.

In the drawings:

Figure 1 is a front elevation of the improved vending machine:

Figure 2 is a rear elevation of the machine with the back removed to show the coin chutes:

Figure 3 is a rear elevation of the vending machine with the back in place;

Figure 4 is a cross sectional view on the line 4—4 of Figure 2;

Figure 5 is a fragmentary vertical trans-

verse sectional view of the vending machine and on an enlarged scale from the showing of Figures 1 to 4 inclusive, the said view being taken on the line 5—5 of Figure 2;

Figures 6, 7, 8, 12, 13, 14 and 15 are fragmentary detail views of the coin-controlled commodity operating means in various positions of service and showing the effects of receiving a slug, then receiving a proper coin upon such means;

Figures 9 and 10 are enlarged views partly in section and showing operation of the coin-controlled commodity operating means to discharge a commodity from the vending machine; and,

Figure 11 is an enlarged face view of the coin-receiving slot member.

Corresponding parts in all the figures are designated by the same reference characters.

Referring with particularity to the drawings, the improved vending machine is designated as an entirety and in one embodiment by A, and such device includes a suitable casing member *a* the size of which is not important, as it may be formed to best accommodate the commodity to be dispensed from the machine. However, in the embodiment of the device shown in the drawings, I have preferred to show the casing as adapted to house small pasteboard cartons *b* in individual compartments 1, 2 and 3 in such casing, and which cartons may contain such edibles as sandwiches, pie, cake, et cetera. The embodiment of the invention might be such as to hold various flavors of chewing gum such as the well-known Wrigley spearmint, double mint, licorice, P-K and the like, in separate compartments, so that when a proper coin is inserted in the vending machine any one of such gums might be dispensed to the purchaser. In the embodiment of the machine shown, I have illustrated the vending machine as adapted to dispense pasteboard cartons containing an edible, and the said casing *a* includes a base member

4, a back 5, a top member 6, and curved members 7 and 8 associated with sides 9 and 10. As illustrated in Figures 1 and 5 the curved members 7 and 8 are spaced from the top and between the top member 6 and a cross-piece 11 which extends between the sides 9 and 10, is a hinged door 12 provided with glass or like panel portions 13. The number of panel portions will depend upon the number of compartments within the cas-

ing, and in the instant case there would be three of such glass panels so that the commodity within such compartments could be viewed and when one of the compartments 5 was empty, if no signaling device was within the compartment to indicate such condition, a purchaser could readily ascertain that all the commodities had been dispensed from such compartment by simply looking 10 through the glass 13 in front of such compartment. The curved front 7 is hingedly associated as shown at 14 with the front 8, and the curved front 8 is spaced from the base as shown at 15. The back member 5 extends above the top member 6, as shown 15 in the figures and for reasons which will presently appear. A sub-back member 16 is likewise provided and this sub-back member acts to maintain the commodity within the 20 various compartments so that when the back 5 is removed access may not be had to such commodity.

In Figure 2 the back 5 has been removed and it will be seen that there are provided in 25 such figure three coin-receiving chutes designated generally by *c*. These coin-receiving chutes are identical of formation and the number thereof will depend entirely upon the number of chambers for different forms 30 of commodities. There may be one of such chutes or there may be many. Considering one of such chutes *c* it will be noted that the same extends along the sub-back member terminating at one end adjacent the top surface 35 of the top 6 as shown at 17, and that the opposite end communicates with a coin-controlled commodity-operating means designated generally by *d*. The back member 5 carries upon that portion which is normally 40 above or partially above, the top 6, a coin slot-receiving member *e* which includes in the embodiment shown a fixed plate member 18 and a movable plate member 19 within the fixed plate member, the fixed plate member being formed with one or more coin-receiving 45 openings 20, as is likewise the movable plate 19, as indicated at 21. A finger-piece 22 is associated with the movable plate 19, and is passed through a slot 23 in the fixed plate 18. The openings 20 are of a size sufficient 50 to just accommodate a coin of a certain denomination, and when a proper coin has been received within such opening it will likewise be received within the opening 55 21 of the movable plate, and upon moving the finger-piece 22, the opening 21 in the plate 19 will bring the coin into registration with the upper portion of one of the coin-receiving chutes *c* and the coin will then be directed 60 through such chute to the means *d*.

Reference to Figure 5 will show that there is likewise provided within the casing a sub-base member 24 normally above the base 4, and that this sub-base member extends 65 transversely of the casing and between the

sides thereof and communicate with a commodity delivery chute *f*. Attention is again directed to the fact that only one coin-receiving chute, one commodity-containing chamber, and one commodity delivery chute is being described, as such elements would be the same for any remaining chambers of the device, it being understood, of course, that partitions would be provided as shown in Figure 4 at 25 and 26 between the different commodity containing chambers and commodity delivery chutes. 70

The coin-controlled commodity operating means *d*, is so called for the reason that when a proper coin is received by such means the same is placed in a position to engage a commodity which is to be discharged through the discharge chute *f*. The means *d* includes in the embodiment shown a lever 27 formed at one end with a coin-receiving pocket or head 28 and at the opposite end with a commodity engaging head 29. Such lever is pivotally carried on a pin 30 at a certain distance between the heads 28 and 29, and which pin is associated with or carried by a carriage member 31. The carriage member includes a block or plate carried on a rod 32, which rod extends transversely of one of the chambers for holding a commodity and is supported on guides 33. The guides would either be secured to one of the sides or both of the sides or carried by the partitions 25 and 26, as of course would be obvious. The construction is such as to permit the said carriage to be drawn from adjacent the sub-back 16 toward the curved front of the casing or toward the commodity delivery chute *f*. Normally the commodity engaging head would be of greater weight than the coin-receiving pocket if the lever was pivoted intermediate such portions. However, if not so pivoted intermediate the heads, the pivotal zone would be such as to at all times move the coin-receiving pocket to a position adjacent the coin-receiving chute so that any coin delivered through such chute would be received in such coin-receiving pocket, and the weight of such coin would be sufficient to cause a downward travel of that portion of the lever bearing the coin-receiving pocket and an upward movement of the commodity engaging head similar to that illustrated in Figs. 6 and 7, the normal position of the lever being substantially as shown in Figure 8. It is intended that the said lever should be so balanced that a coin of a certain weight is sufficient to tip the lever as aforesaid, but a coin of lesser weight will not produce a full excursion of the lever. By full excursion is meant such a movement as would permit the commodity engaging head 29 to engage a commodity. The excursion of the lever, however, is in a measure limited by a member 34 carried by the block or plate forming 80

a portion of the carriage member 31. In other words, this part 34 may be a wire loop or the like which will limit the upward travel of the commodity engaging head, as well as limiting the downward travel thereof. The said commodity engaging head is notched as shown at 35, and when a coin is received in the coin-receiving pocket 28 the notch 35 will be brought into a position adjacent the top surface of the sub-base 24 and slightly above the same. The sub-back 16 is cut away as shown at 36 so as to permit the means *d* with its carriage to extend through the same and so that the said means *d* may be in such a position as to be adjacent the coin-receiving chute at its lower end. The cut-away portion 36 of the sub-back also includes a cut-away portion for the commodity engaging head 29 when it is tipped upwardly as illustrated in Figure 6. The coin-receiving pocket 28 comprises two spaced members 37 and 38, one of which, 37, is substantially circular in outline, while the other is cut away on a chord, as shown at 39, and such portions 37 and 38 are spacedly joined together where they connect with the lever 27, as illustrated at 40 and openly spaced apart for the remaining distance so that any object received in such pocket, that is, between the portions 37 and 38 would not be retained between said portions. However, when the lever 27 is in the position, as illustrated, for instance, in Figure 6 in dotted lines, the two spaced portions 37 and 38 are in such a position that a coin will be received between the same from the coin-receiving chute *c* and such coin is prevented from escaping as between such portions 37 and 38 by a coin guard 41. This coin guard includes a plate which is bent straight downwardly and then curvedly bent as illustrated at 42 and 43 respectively, so that the coin is retained within the pocket during a certain movement of the carriage carrying the lever. In the embodiment shown, and assuming that a proper coin has been delivered through the chute *c* into the pocket of the lever to tip the lever into the full line position of Figure 6, the commodity-engaging head will be brought upwardly as illustrated in such figure and if the carriage were then moved inwardly of the casing *a* the notch 35 of the commodity-engaging head would engage the top surface of the sub-base and ride thereon, and if any commodity cartons *b* were within the compartment such commodity-engaging head would engage against a side or end as 44 of the commodity carton and push the same forwardly and from beneath other members of such commodity cartons as illustrated in Figure 5 to such a position that the commodity carton would be tipped sufficiently to deliver the same through the commodity delivery chute *f* and outward through the space 15 between the parts 4 and 8 of such casing. This function of drawing the means *d* forwardly or within the casing *a* is accomplished through the medium of a commodity operating lever *g* and which lever extends through a transverse bore in the part 8 to where it is associated with the carriage member 31. An outward pull upon a finger-piece 45 mounted exterior of the casing *a* and upon the operating lever *g* will slide the carriage member 31, including the rod 32 carried on the guides 33, forwardly of such casing, and a distance sufficient to permit the ready discharge of a commodity from the casing *a*. The sub-base member is slotted as illustrated in Figure 4 at 46, so that the commodity engaging head will partially project through the slot 46 with the walls forming the notch engaging the top surface of such sub-base until a further cut-away portion 47 is reached, whereupon the commodity-engaging head will no longer contact with such top portion of the sub-base but will drop through such cut-away portion 47, and into a substantially horizontal position or the position as illustrated in Figure 8. The cut-away portion 47 is at a distance sufficient to assure a full discharge of a commodity through the commodity delivery chute *f*. The said commodity operating lever *g* is spring-actuated in one direction; that is to say, a curved spring as illustrated in dotted lines in Figure 5 at 48, is connected with the base 4 as illustrated at 49 and with the carriage member 31 as illustrated at 50, and when the commodity operating lever has made a full excursion, which would be an excursion sufficient to allow the commodity-engaging head of the lever 27 to drop through the slot 47, the spring would be in an extended position as illustrated, for instance, in Fig. 10 in dotted lines at 51, and a releasing of the finger-piece 45 would immediately allow the spring to re-act, the top portion of the commodity-engaging head would be beneath the sub-base, and the means *d* would, under actuation of the spring, be again brought to a position where it communicated with the coin-receiving chute *c*. To assure that the commodity-engaging head will pass through the cut-away portion 47 or in case the commodity-operating lever *g* is not moved a sufficient distance so that the commodity-engaging head 29 reaches the cut-away portion 47, that the said lever be tipped to a horizontal position as illustrated in Figure 8, after a commodity has been discharged, I have provided a member 52 which may comprise a bent wire spring at all times adapted to engage a portion of the lever 27 adjacent the coin-receiving pocket 28, as illustrated in Figure 8 at 53. The coin guard 41 is of relatively short width and of a width just sufficient to hold the coin within the pocket until the commodity-engaging head has its notched portion in 130

engagement with the top surface of the sub-base, whereupon reaching the termination of such coin guard any coin received in such pocket will be permitted to roll from such pocket or fall therethrough and on to a coin discharge chute 54 into a coin tray 55.

Placed between the part 7 of the casing and a portion of commodity chute *e* is a hinged door *h*, the door being hinged to the part 7, as illustrated at 56, and normally the lower edge of such door will contact with the commodity chute as illustrated in dotted lines in Fig. 5. When a commodity is in the act of being discharged through the commodity chute *f* it will be noted that the door will be tipped upwardly as illustrated in Figure 5 in full lines. There is likewise provided a counter *j* having an arm 57 in the path of movement of the commodity being discharged so that the number of cartons of the commodity discharged can be ascertained. After the commodity has been discharged through the space 15, the door *h* will swing back into the position illustrated in dotted lines, and it is obvious that any one attempting to reach up through the space 15 in an attempt to reach the commodities within the commodity chambers will be prevented from doing so by said door as the door can move in one direction only, outwardly, as illustrated in Fig. 5.

The operation, uses and advantages of the vending machine are as follows:

Assume that the vending machine appears as substantially as shown in Figure 1 with commodities in each of three chambers as illustrated at 1, 2 and 3. A proper coin, say a ten cent piece is inserted in the coin-receiving opening of the member *e*, the finger-piece 22 moved, and the coin delivered through one of the coin-receiving chutes *e* where it contacts with the coin-controlled commodity operating means, tipping the lever constituting a portion of the same to where the commodity-engaging head is in a position to engage a carton containing one of such commodities. Outward movement of the commodity operating lever *g* will then discharge one of the commodities through the commodity discharge chute *f*, a commodity within the commodity chamber directly above such commodity discharged is retained in the commodity chamber due to the fact that the piece 11 of the casing will contact with a side thereof as illustrated at 58 to hold the commodity in position and prevent its discharge along with a commodity being moved from beneath the same. The commodity being discharged, as illustrated in Fig. 5 will swing the door outwardly, contact with the counter lever 57, be discharged through the opening 15, and a releasing of the commodity operating member will allow a restoration of the lever

27 into a position substantially as shown in Figure 2.

Assume now that a slug of say the diameter of a ten cent piece and made of aluminum is inserted through the coin-receiving chute; the said slug will be received in the coin-receiving pocket but being lighter than the ten cent piece, the pocket end of the lever 27 will not be moved downwardly due to the greater weight of the head 29 or the position of the pin 30, and an outward pull upon the commodity operating lever *g* would only cause the commodity-engaging head to pass beneath the sub-base 24 and no commodity would be discharged from the commodity chamber. Suppose now that a ten cent piece were placed in the chute. The ten cent piece would contact with a portion of the periphery of the slug and its weight plus that of the slug would of course tip the lever downwardly, as illustrated in Fig. 13, the said slug being indicated by dotted lines. In this instance it is to be noted that the periphery of the slug, if it is of the same diameter as a ten cent piece, is slightly above the cut-away portion 39 of the portion 38 of such coin-receiving pocket, with the result that the ten cent piece as shown in Fig. 14 and designated as 59, is not received within the pocket. This position is also illustrated in Fig. 14. If now the operating lever *g* is pulled outwardly the notched portion 35 of the commodity-engaging head will engage the top surface of the sub-base 24 and be in a position to engage a side of the commodity carton *b*, and upon such outward movement of the commodity operating lever the ten cent piece 59 will slide off the slug and be dropped on to the coin guard as illustrated in Fig. 15 at 60, to where it may be recovered either by the same striking the chute 54 and falling into the tray or dropping upon the base 4. In other words, a slug will operate the machine only when the slug fails to roll off of the coin receiving pocket and when a coin of proper denomination and weight is then received upon such slug to operate the means *d*, and it is of course obvious that the slug would roll from the pocket member and on to the chute 54 and into the tray. Thus impairment of the machine due to using slugs will ordinarily not result.

The different members of the casing may be securely locked in any approved manner, the back 5 may be secured by means of any form of Yale lock or padlock or the like, as may the glass enclosed front of the vending machine, and the part 7 may be locked by passing a pin 61 through aligned openings in the parts 7 and 11, as shown in Fig. 5, it being noted that said pin is not accessible except by opening the glass front.

It is obvious that various changes and

modifications may be made in practicing the invention, in departure from the particular showing, without departing from the true spirit of the invention.

5 Having thus disclosed my invention, I claim and desire to secure by Letters Patent:

1. In a vending machine, a commodity chamber formed with a slotted base, a slide- 10 able carriage under said base, a lever pivoted on said carriage transversely of the commodity chamber and comprising a commodity engaging head at one end and a coin pocket at its opposite end, the lever normally lying rearward of the commodity chamber and tilttable when a coin is received within the pocket to bring the commodity engaging head in alignment with the slot in the base and in rear of the lowermost commodity in the chamber, means for sliding the carriage and lever forward so that the commodity engaging head will move in the base slot and engage and eject the lowermost commodity from the chamber, the coin pocket being open to permit the escape of a coin, and a guard for retaining the coin within the pocket and permitting escape thereof during the forward movement of the carriage. 15
2. In a vending machine, a commodity chamber formed with a slotted base, a slide- 20 able carriage under said base, a lever pivoted on said carriage and comprising a notched commodity engaging head at one end and a coin pocket at its other end, a coin chute, the lever normally lying rearward of the commodity chamber with its coin pocket in the path of the coin chute and tilttable when a coin is received within the pocket to bring the notch in the commodity head in alignment with one edge of the slot in the base and the commodity head at the rear of the lowermost commodity in the chamber, the coin pocket being open at one side, a guard 25 adjacent the open side of said pocket to retain the coin within the pocket, means for sliding the carriage and lever forward so that the notch of the commodity engaging head will ride upon the edge of the slot of the base and the said head will engage and eject the lowermost commodity from said chamber, while the coin in said pocket will pass beyond said guard and drop from the pocket, means for swinging said lever back 30 to its normal position and its commodity engaging head below said base, and means for subsequently moving the carriage back to its normal position. 35
3. In a vending machine, a commodity chamber formed with a base provided with a slot therein, on which base the lowermost commodity in the chamber rests, a carriage mounted to slide forwardly and backwardly under said base, a lever pivotally mounted on said carriage and formed with a notched commodity-engaging head on one end and with a coin-receiving pocket on its other end, 40 a coin chute, said carriage normally resting with its lever rearwardly of said commodity chamber and with said coin-receiving pocket under said coin chute, said lever being constructed and arranged so that when said coin pocket receives a coin from said chute the lever will be swung by the coin into such position that the notch in said commodity-engaging head will align with one edge of said slot in said base and the commodity head will rest at the rear of the lowermost commodity in said chamber, means for drawing said carriage and lever forwardly so that the commodity-engaging head will extend through said base slot and the notch in said commodity-engaging head will receive one edge of said base slot and said commodity head will engage and eject the lowermost commodity from said chamber, means for retaining the coin within said pocket until said commodity-engaging head is drawn into said chamber and the notch in said head has received the edge of said base slot, means for swinging said lever back to its normal position and its commodity engaging head below said base when the commodity has been ejected by said head, and means for subsequently moving the carriage back to its normal position. 45
4. In a vending machine, a commodity chamber formed with a base provided with a slot therein, on which base the lowermost commodity in the chamber rests, a carriage mounted to slide forwardly and backwardly under said base, a lever pivotally mounted on said carriage and formed with a notched commodity-engaging head on one end and with a coin-receiving pocket on its other end, a coin chute, said carriage normally resting with its lever rearwardly of said commodity chamber and with said coin-receiving pocket under said coin chute, said lever being constructed and arranged so that when said coin pocket received a coin from said chute the lever will be swung by the coin into such position that the notch in said commodity-engaging head will align with one edge of said slot in said base and the commodity head will rest at the rear of the lowermost commodity in said chamber, means for drawing said carriage and lever forwardly so that the commodity-engaging head will extend through said base slot and the notch in said commodity-engaging head will receive one edge of said base slot and said commodity head will engage and eject the lowermost commodity from said chamber, means for limiting the movement of the lever under the weight of a coin in the pocket to such position that should another coin be dropped through said chute it would rest upon the coin in the pocket with its upper portion in the lower end of the chute, the upper edge 50

of the rear wall of the pocket being cut away to allow the lever to be drawn forwardly and said other coin to drop behind the lever, means for retaining the effective coin in said pocket until said commodity-engaging head is drawn into said chamber and the notch in said head has received the edge of said base slot, means for swinging

said lever back to its normal position and its commodity-engaging head below said base when the commodity has been ejected by 10 said head, and means for subsequently moving the carriage back to its normal position.

In testimony whereof, I have signed my name to this specification.

ORSON N. KELLY.
